CLAIM

The ornamental design for a smart card with chip contact pad, as shown and described.

DESCRIPTION

FIG. 1 is a front bottom perspective view for a smart card with chip contact pad, showing my new design.

FIG. 2 is a rear bottom perspective view of FIG. 1 thereof; FIG. 3 is a front elevational view of FIG. 1 thereof; and, FIG. 4 is a rear elevational view of FIG. 1 thereof.

The broken lines indicate unclaimed portions of the smart card with chip contact pad and form no part of the claimed design.
